US00D820802S

(12) **United States Design Patent** (10) Patent No.: **US D820,802 S**
(45) Date of Patent: **** Jun. 19, 2018**

(54) **UNIT FOR CONFERENCE SYSTEM**

(71) Applicant: **Sennheiser electronic GmbH & Co. KG**, Wedemark (DE)

(72) Inventors: **Matthis Hamann**, Grünwal (DE); **Christian Rogge**, München (DE); **Christian Moser**, München (DE); **Jan König**, München (DE); **Florian Wübert**, München (DE)

(73) Assignee: **Sennheiser electronic GmbH & Co. KG**, Wedemark (DE)

(**) Term: **15 Years**

(21) Appl. No.: **29/563,968**

(22) Filed: **May 10, 2016**

(30) **Foreign Application Priority Data**

Nov. 10, 2015 (EM) 002853838

(57) **CLAIM**

The ornamental design for a unit for conference system, as shown and described.

DESCRIPTION

FIG. 1 is a left side view of a unit for conference system embodying the invention;

FIG. 2 is a rear view thereof;

FIG. 3 is a right side view thereof;

FIG. 4 is a front view thereof;

FIG. 5 is a top view thereof;

FIG. 6 is a bottom view thereof; and,

FIG. 7 is a front-bottom perspective view thereof.

1 Claim, 7 Drawing Sheets
